COMBINED BOTTLE STOPPER AND LIQUID DISPENSER

Claude Gray, Marysville, Calif.

Filed Nov. 13, 1959, Ser. No. 58,335

Term of patent 3½ years

(Cl. D2—3)

Fig. 1

Fig. 3

Fig. 1 is a perspective view of a combined bottle stopper and liquid dispenser, showing my new design; Fig. 2 is a side elevational view thereof; and Fig. 3 is a rear elevational view of the same.

I claim:

The ornamental design for a combined bottle stopper and liquid dispenser, as shown.
